UNITED STATES PATENT OFFICE.

SAMUEL EDELSON, OF NEW YORK, N. Y.

DESIGN FOR A DOORLOCK.

Application filed February 19, 1923. Serial No. 5,201. Term of patent 14 years.

To all whom it may concern:

Be it known that I, SAMUEL EDELSON, a citizen of the United States, residing in the borough of Manhattan, in the city and State of New York, have invented a new, original, and ornamental Design for Doorlocks, of which the following is a specification, reference being had to the accompanying drawing, forming part hereof.

Figure 1 is an elevation and Figure 2 is a plan view of a doorlock showing my new design.

The lock and keeper are sold as a unitary device.

I claim:

The ornamental design for door lock, as shown.

SAMUEL EDELSON.
